UNITED STATES PATENT OFFICE

ROBERT MAUTSCH, OF BRUSSELS, BELGIUM, ASSIGNOR TO MANUFACTURE GENERALE METALLURGIQUE, SOCIÉTÉ ANONYME, OF BRUSSELS, BELGIUM, A COMPANY OF BELGIUM

HEAT EXCHANGE APPARATUS

Application filed November 25, 1931, Serial No. 577,329, and in Belgium November 28, 1930.

The present invention relates to apparatuses such as radiators, evaporators or the like, the heat exchange surfaces whereof are constituted by corrugated or puckered fins, threaded upon substantially parallel tubes to interconnect two or more tubes appertaining to one same unit of the apparatus. When said fins are threaded upon said tubes and are thereafter shrunk thereto by expansion of the tube, it frequently occurs that the stress of said expansion slightly flexes said tubes or otherwise forces them out of parallelism, whereby the appearance of the apparatus is impaired and difficulties may arise when the members are assembled. Furthermore, when constructing apparatuses whose corrugated fins must contact with each other to constitute a honeycomb pattern, great care is required in order to ensure that the apices of the corrugations of adjacent fins face each other accurately, since otherwise said fins intermesh instead of remaining spaced apart and the desired object is not attained. Care also should be taken to avoid hindering the freedom of circulation of the fluid surrounding the tubes.

According to my invention, these difficulties are very simply obviated by the interposition of flat fins between said corrugated fins, and the use of corrugated fins comprising groups of larger corrugations and of smaller corrugations preferably arranged in alternating relation. Said flat fins constitute rigid stays between the tubular members and hold the latter securely and accurately parallel with each other when said corrugated and flat fins are shrunk thereon and said corrugated fins, being separated from each other by said flat fins, cannot intermesh even though their apices may not coincide, a function which the corrugated fins alone cannot fulfil, since they are easily extended and contracted transversely of their corrugations.

This invention therefore allows the corrugated fins to be formed with less accuracy than has been required hitherto and obviates the necessity of scrapping those of said corrugated fins which are not exactly to gauge, since the flat fins automatically ensure the

uniform spacing of the corrugated fins between which they are interposed. For the same reason it is no longer necessary, in order to form a honeycomb pattern, that the apices of the corrugations of the fins should register accurately with each other, a novel arrangement becoming possible, on the contrary, if the apices of the corrugations of one fin are placed opposite the hollows in the corrugations of the fin adjacent thereto, the flat fin interposed therebetween preventing the intermeshing of the apices of one corrugated fin with the hollows in the other fin.

My invention is applicable to all forms of heat exchange apparatus members having corrugated fins threaded upon tubes, whatever may be the arrangement and shape of the corrugations or creases thereof, or the relative dimensions of said corrugations and of the tubes passing through said fins. It is likewise immaterial whether the fins are spaced apart from or in contact with each other, or whether they all contact with each other or only contact in groups. Furthermore, flat fins may be caused to alternate regularly with corrugated fins, or be merely interspersed between the latter as desired.

The attached drawing illustrates by way of example some portions of heat exchange members having corrugated fins and flat interposed fins, according to this invention. In said drawing:

Fig. 1 is a plan view of an arrangement wherein the corrugated fins are spaced apart from the flat fins,

Fig. 2 illustrates a similar member whereof the corrugated fins and the flat fins are in contact, and

Fig. 3 shows a modification to the arrangement of Fig. 2.

Each of the heat exchange apparatus members illustrated in the drawing comprises two parallel tubes *a* wherein, for example, the refrigerating or the heating fluid is caused to flow, and corrugated fins *b* and flat fins *c*, threaded upon said tubes to constitute the contact area for the other fluid flowing therebetween. Fins *b* have groups of large corrugations *m* alternating with groups of smaller corrugations *n*. Due to the considerable ex-

tension provided by their corrugations, fins *b* afford a large contact area whilst the flat fins *c*, which alternate with said corrugated fins *b*, act as rigid stays for the tubes *a*, while 5 affording heat exchange areas likewise.

Fins *b* and *c* (Fig. 1) may be spaced apart as desired, said space being adjusted by inserting between said fins suitable distance pieces, which are withdrawn after the fins 10 have been shrunk upon the tubes.

In Fig. 2, the fins are in contact with each other to form a structure somewhat resembling a honeycomb, the corrugated fins *b* being so arranged that the apices of the corrugations of adjacent fins face each other. Said apices bear against the flat fin *c* interposed between two adjacent corrugated fins, and the spaces between the latter cannot therefore become irregular, even though their 20 apices should be slightly offset, whereas some intermeshing of said offset corrugated fins would be unavoidable if no flat fin were inserted therebetween. The small corrugations *n* are preferably provided where the fins are 25 intersected by the tubes *a*, in order to leave a free space for the circulation of the surrounding fluid on all sides of the tubes.

An example is illustrated in Fig. 3 where in such offsetting is intentional and is carried 30 to the point that the apices of one fin *b* face the depressions in the adjacent fin *b*, whereby a novel honeycomb arrangement is obtained.

I claim:

35 1. In a heat exchange apparatus, substantially parallel tubular members, fins having alternating groups of large and small corrugations formed therein, and flat fins, said

corrugated fins and flat fins being threaded and shrunk upon said tubular members substantially at right angles to the same, and said flat fins being interposed between said corrugated fins said small corrugations being 70 spaced away from said flat fins.

2. In a heat exchange apparatus, the combination of substantially parallel tubular members, corrugated fins and flat rigid fins threaded and shrunk upon said tubular members at substantially right angles thereto, said rigid flat fins being in alternate relationship with said corrugated fins and constituting rigid stays between said tubular members said corrugated fins having alternating groups of larger and smaller corrugations, said tubular members extending through said smaller corrugations, the apices of said larger corrugations contacting with said flat fins, and the apices of said 85 smaller corrugations being spaced away from said flat fins.

3. In a honeycomb heat exchange apparatus, the combination of substantially parallel tubular members, and corrugated fins and rigid flat fins threaded and shrunk upon said tubular members at substantially right angles thereto, said rigid flat fins alternating with said corrugated fins, and said corrugated fins and rigid flat fins bearing 90 against and supporting each other in a uniform honeycomb formation between said tubes and being spaced apart from each other in proximity to said tubes.

In testimony whereof I have signed my 100 name to this specification.

ROBERT MAUTSCH.
